CHAIR HEAD REST

Robert West, Ponca City, Okla.

Application December 1, 1931. Serial No. 578,363

3 Claims. (Cl. 155—177)

The present invention relates to chair head rests of the character used in connection with barber chairs and the like.

The object of the invention resides in the provision of a head rest having a wide range of adjustment, and capable of being quickly and conveniently arranged in any desired position for the comfort of the user.

Another object of the invention resides in the provision of a head rest capable of being easily adjusted to the desired position, or wholly disposed in an out of the way position when not in use, thus eliminating the necessity of removing the head rest from the chair, as is now customary.

The invention also contemplates a head rest which is simple in construction, including a paper roll, and a novel construction of means for clamping the paper over the head rest.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a side elevation of the head rest, showing by dotted lines the position it occupies when not in use.

Figure 2 is a front elevation.

Figure 3 is a transverse sectional view showing how the head rest is held in adjusted position.

Figure 4 is a bottom plan view.

Figure 5 is a fragmentary view showing how the springs and paper roll are supported by the frame of the head rest.

Figure 6 is a fragmentary view of the frame.

Figure 7 is a sectional view on line 7—7 of Figure 6.

Figure 8 is a fragmentary view of one of the springs.

Referring to the drawings in detail, 10 indicates a shank upon which the head rest is mounted, and this shank is provided with a series of openings 11 so that the shank can be adjusted vertically on the chair (not shown) in the usual manner. The upper end of the shank is slightly thickened as at 12, and characterized with a notched segment 13 for a purpose to be herein-after described.

The head rest proper comprises an open frame 55 of substantially rectangular contour in plan, but

which is curved transversely as illustrated. The opposed end members 14 of the frame are provided with aligned slots 15, each slot having communication with a recessed portion 16. The corresponding slots of these end members receive the adjacent ends of coiled springs 17, each spring having its outer convolutions extended as at 18, as illustrated in Figure 8. These extensions 18 are received by the slots 15, and hold the springs associated with the frame, but in a manner whereby any one or more springs can be conveniently removed, and replaced by a new spring as the occasion may require. These springs support a pad 20 which may be constructed in any suitable manner and from any suitable material.

Also supported by the end members 14 of the frame is a transverse shaft 21 upon which is mounted a paper roll 22, the paper being unwound from the roll and extended over the pad 20, and passed downwardly between the pad and the rear member 23 of the frame. The paper is clamped to the rear member 23, preferably by means of a plate 24, which is substantially co-extensive in length with the rear member 23 of the frame. This plate is carried by a rock shaft 25 which is journaled between the end members 14 of the frame and provided with springs 26 which normally maintain the plate 24 in clamping position. The shaft 25 is equipped with a thumb engaging member 27, so that the shaft 25 can be quickly and conveniently manipulated to release the paper from the clamping plate 24. The shaft 21 can be removed from the frame when desired, as it is slidably received by aligned openings in the end members 14. One end of the shaft 21 is provided with a head 28 adapted to lie flush with the outer surface of the adjacent end member 14 as shown in Figure 5, and held immovably associated with the frame by means of a plate 29. This plate is pivoted on the end member 14 and can be easily swung to either its active or inactive position. In other words the plate 29 can be swung to uncover the head 28 of the shaft 21 so that the latter can be easily removed from the frame.

The front member 30 of the frame is provided with spaced depending apertured lugs 31 which receive a bolt 32 which is pivoted in the thickened end portion 12 of the shank. Consequently the head rest is mounted for pivotal adjustment on the shank, so that the head rest can be arranged at any angle with relation to the shank 10 for the comfort of the user. The head rest automatically cooperates with the grooved segment 13 to hold itself fixed with relation to 110

the shank in its given position for use. For this purpose the front member 30 supports a hinged-
ly mounted latch 33 from the under side of which
depends a finger 34 which slides through an
opening 35 in the front member 30 of the frame.
Pivotedly connected with the free end of the
latch 33, as at 36, is a headed pin 37 which slides
through an opening in the front member 30 of
the frame. Surrounding this pin is a coil spring
38 which bears against the frame and head of
the pin to normally maintain the latch 33 in its
active position.

In practice, the shank 10 can be adjusted vertically with relation to the chair, upon which
15 the head rest is used in the ordinary well known
manner, while the head rest proper can be swung
upon its pivot 32 to occupy any desired angle with
relation to the shank 10 for the comfort of the
user. It is only necessary to press inwardly on
20 the headed pin 37, whereupon the latch 33 is ele-
vated and the finger 34 removed from the grooved
segment 13. Under these conditions the spring
38 is compressed and placed under tension. After
the head rest has been adjusted to the desired
25 position, the pin 37 is released, whereupon the
spring 38 automatically returns the latch 33 to
its active position, with the finger 34 received
by the adjacent groove of the segment 13. When
use of the head rest is not necessary, it can be
30 swung upon its pivot to occupy an out of the
way position as clearly illustrated by dotted lines
in Figure 1. In this position the head rest is
wholly arranged at the rear of the standard 10
and suspended from the upper end thereof, there-
35 by eliminating the necessity for removing the
head rest from the chair as is customary with
present day constructions.

The paper can be also easily unwound from
the roll 22 and clamped against the rear mem-
40 ber 23 of the frame, and released therefrom by
manipulating the thumb engaging member 27.
The structure in its entirety comprises a mini-
mum of parts and can be quickly and conven-
iently manipulated for the purpose intended.

45 While it is believed that from the foregoing de-
scription the nature and advantages of the invention
will be readily understood, I desire to have
it known that I do not limit myself to what is
herein illustrated or described and that such

50

changes may be resorted to when desired as fall
within the scope of what is claimed.

What is claimed is:

1. In combination, a shank, a grooved segment
supported by the upper end thereof, a head rest
including a frame pivotally mounted on the up-
per end of the shank and capable of being ar-
ranged at any desired angle thereto for use, a
latch hingedly supported on the frame and in-
cluding a finger slidably through an opening in
the frame to engage said segment, a headed pin
pivotally connected with the free end of the latch
and slidable through an opening in the frame,
and a coiled spring surrounding said pin and nor-
mally maintaining the latch in its active posi-
tion.

2. In combination, a shank, a grooved seg-
ment supported by the upper end thereof, a head rest
including a frame pivotally mounted on the up-
per end of the shank and having spaced open-
ings in the lowermost member thereof, a latch
plate hingedly mounted on said member and nor-
mally arranged parallel therewith, a finger de-
pending centrally from said plate and passed
through one of said openings in said member to
engage said segment, and yieldable means con-
nected with the free end of the plate and slidable
through the other of said openings of the mem-
ber to normally maintain said finger engaged
with said segment.

3. In combination, a shank, a grooved segment
supported by the upper end thereof, a head rest
including a frame pivotally mounted on the up-
per end of the shank and having spaced open-
ings in the lowermost member thereof, a latch
plate hingedly mounted on said member and nor-
mally arranged parallel therewith, a finger de-
pending centrally from said plate and passed
through one of said openings in said member to
engage said segment, a headed pin pivotally
connected with the free end of said latch plate
and slidable through the other of said openings
of the member, and a coiled spring surrounding
said pin and interposed between the head of the
latter and said member to normally maintain the
finger of said latch plate engaged with said seg-
ment.

ROBERT WEST.
